Electric & Manufacturing Company, East
Pittsburgh, Pa., a corporation of Pennsylvania

Application January 12, 1937, Serial No. 120,232

7 Claims. (Cl. 257—43)

Our invention relates to surface condensers, more particularly of the marine type, and it has for an object to provide a condenser with beam members connected thereto and which function, not only to support the condenser, but to cooperate with the latter to provide a supporting or bed construction for turbines and the like.

A further object of our invention is to provide a condenser having its shell welded to end plates constituting webs of supporting beam members whose outer ends are carried by supports, the beam members being attached to the supports at one side of the condenser so as to resist movement of the beam members bodily in the directions of their length and the beam members being free to move horizontally with respect to the supports at the other side of the condenser to accommodate expansion and contraction thereof as well as of the condenser.

These and other objects are effected by our invention as will be apparent from the following description and claims taken in connection with the accompanying drawings forming a part of this application, in which:

Fig. 1 is a top plan view of a power plant incorporating the improved condenser arrangement;

Fig. 2 is a side elevation of the apparatus shown in Fig. 1 with a portion of the casing structure broken away to show the gearing and the coupling;

Fig. 3 is an end elevational view of the apparatus shown in Fig. 1;

Fig. 4 is a view similar to Fig. 2 but showing a modified arrangement;

Figs. 5, 6, and 7 are detail sectional views taken along the lines V—V, VI—VI and VII—VII of Fig. 2; and,

Figs. 8 and 9 are detail views taken along the lines VIII—VIII and IX—IX of Fig. 4.

Referring to the drawings more in detail, there is shown a condenser having a shell 10 enclosing a nest of tubes 11 connected to tube plates 12. The shell 10 is welded to end plates 13 to which the tube plates 12 are connected by stud bolts 14, the latter also preferably holding the water boxes 15 in place with respect thereto.

The end plates 13 constitute widened intermediate portions 16 of the webs 17 of the beams or girders, at 18, the beams or girders being constituted by the webs and by suitable strengthening and stiffening flanges 19.

As shown, the beams or girders 18 have their ends, at one side of the condenser, carried by supports 20 formed on the casing 21 of the reduction gearing, at 22. The ends of the beams or girders, at the other side of the condenser are carried by supports 23 formed by any suitable fixed structure.

The beams and the condenser constitute convenient means for supporting apparatus, for ex-

example, the high-pressure turbine 25 and the low-pressure turbine 26. Preferably, a cross beam 27 is arranged between the beams 18 and connected thereto. The condenser shell 10 carries a supporting structure 28 spaced from and arranged substantially parallel to the cross beam 27.

The high-pressure turbine is supported at the end adjacent to the gearing by means of a pedestal 29 carried by the cross beam 27 and at the other end by means of a flexible I-beam section 30 mounted on the structure 28, the I-beam section having its web arranged transversely of the turbine and being, therefore, capable of flexing to accommodate for axial expansion and contraction of the high-pressure turbine.

The low-pressure turbine 26 has its end adjacent to the gearing preferably supported by means of an I-beam section 31 carried by the cross beam 27 and extending transversely of the turbine and flexing to provide for expansion and contraction, the exhaust end of the low-pressure turbine being connected to and supported by the condenser shell.

The beams or girders 18 should be arranged to provide for their expansion and contraction as well as expansion and contraction of the condenser with minimum disturbance of the driving connections between the spindles 32 of the turbines and the pinion spindles 33 of the reduction gear. Accordingly, in the embodiment shown in Figs. 1, 2, 6, and 7, the beams 18 have their ends, at the side of the condenser adjacent to the reduction gear, connected by bolts or rivets 34 to the supports 20, the opposite ends of the beams 18 being free to slide endwise and laterally on the supports 23. In this embodiment, therefore, the beams 18 are capable of expanding and contracting lengthwise with respect to the supports 20 and they have sufficient inherent flexibility axially of the condenser to accommodate for expansion and contraction of the condenser shell.

In the second form of our invention, the necessity for the small amount of flexing on the part of the beams 18 to accommodate expansion and contraction of the condenser is avoided or very largely reduced by means of the I-beam sections 36 fastened to the supports 20 and having adjacent ends of the beams 18 secured thereto, the I-beam sections 36 having their webs arranged coplanar with or parallel to the webs 17. The other ends of the beams 18 in Fig. 4 may be slideable in fore-and-aft and athwartship directions with respect to supports carried by the ship's structure, as shown in Fig. 2, or such ends may be fastened to the upper ends of vertical columns 37 which are laterally flexible in all directions.

While the ends of the beams 18 adjacent to the gear case are connected to the latter and thereby hold the turbines in predetermined relation with

respect to the reduction gearing, other provisions should exist to restrict the condenser and beam aggregate from shifting laterally at the end remote from the reduction gearing and disturbing the relation of the turbines and the gearing as well as the relation of the condenser to its auxiliaries. Accordingly, we provide plates 40 attached at one end to the ship's structure at 41 and having its other end welded to the condenser shell.

10 While the aforesaid two means of anchoring the condenser and beam aggregate necessitate small movements to accommodate for expansion and contraction while maintaining the turbines in proper relation with respect to the gearing, nevertheless, the support and the turbines may undergo a certain amount of expansion and contraction, particularly in a vertical direction, resulting in displacement of the turbine spindles with respect to the pinion spindles 33. For the latter reason, the spindles 32 and 33 are connected by couplings capable of accommodating misalignment. For example, in Fig. 2, we show the spindles 32 and 33 having their adjacent ends provided with peripheral teeth 42 and 43 encompassed by a muff member 44 having internal teeth meshing with the teeth 42 and 43, the muff member being of adequate length to take care of any misalignment.

30 While we have shown our invention in several forms, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. In a power plant condenser arrangement, supports arranged to provide a space therebetween; a pair of spaced beam members providing a supporting bed construction, spanning said space, and having their outer ends carried by said supports; and a condenser including a shell located in said space and end plates for the shell formed by webs of the beam members.

2. In a power plant condenser arrangement, supports arranged to provide a space therebetween; a pair of spaced beam members providing a supporting bed construction, spanning said space, and having their outer ends carried by said supports; and a condenser including a shell located in said space, end plates for the shell and formed by webs of the beam members, a nest of tubes within the shell, tube plates connected to ends of the tubes, water boxes, and means for securing the tube plates and the water boxes to the end plates formed by the beam member webs.

3. In a power plant condenser, a shell, a pair of horizontally-extending beam members providing a bed construction, end plates connected to the shell ends and formed by webs of said beam members, a nest of tubes within the shell, tube plates for the tubes, water boxes, means for securing the tube plates and the water boxes to the end plates formed by the beam member webs, means for supporting the outer ends of the beam members at one side of the condenser so as to resist bodily movement thereof lengthwise, and means for supporting the outer ends of the beam

members at the other side of the condenser so as to provide for movement thereof horizontally in any direction.

4. The combination with a power plant condenser, of means for supporting the condenser including a pair of beam members, said beam members having intermediate and depending widened portions joined to the ends of the condenser, means for supporting the outer ends of the beam members at one side of the condenser so as to resist movement thereof bodily in the direction of their length, and means for supporting the outer ends of the beam members at the other side of the condenser so as to provide for movement thereof to accommodate for expansion and contraction of the condenser and for contraction and expansion of the beam members in the direction of their length.

5. The combination with a power plant condenser, of means for supporting the condenser including a pair of beam members having intermediate and depending widened portions joined to the ends of the condenser, first supports for the ends of the beam members at one side of the condenser, second supports for the ends of the beam members at the other side of the condenser, and means for attaching the first supports to the corresponding ends of the beam members to resist movements thereof bodily in the direction of their length, said second supports and the corresponding ends of the beam members being constructed and arranged to provide for movement of the beam members so as to accommodate expansion and contraction of the condenser and of the beam members in the direction of their length.

6. The combination with a power plant condenser, of means for supporting the condenser including a pair of beam members having intermediate and depending widened portions joined to the ends of the condenser, first supports for the ends of the beam members at one side of the condenser, second supports for the ends of the beam members at the other side of the condenser, and means for connecting the ends of the beam members to the first and second supports, said first support being flexible in the direction of length of the condenser and the second supports being flexible both in the direction of length of the condenser and in the direction of length of the beam members.

7. The combination with a power plant condenser, of means for supporting the condenser including a pair of beam members having intermediate and depending widened portions joined to the ends of the condenser, means for supporting the outer ends of the beam members at one side of the condenser so as to resist movement of the beam members in the direction of their length, means for supporting the outer ends of the beam members at the other side of the condenser so as to provide for movement thereof to accommodate for expansion and contraction of the beam members in the direction of their length and for expansion and contraction of the condenser shell, and means for anchoring the condenser shell midway of its length against movement in the direction of its length.
